APPARATUS FOR SLITTING LEATHER

John R. Ritzinger and Fred G. Bevans, Kansas City, Mo., assignors to Wilson-Jones Company, Chicago, Ill., a corporation of Massachusetts

Application August 24, 1931. Serial No. 558,930

12 Claims. (Cl. 69—15)

This invention relates to an apparatus for forming book covers.

In the manufacture of ring books wherein a single ply leather or imitation leather, or the like, cover is used, it is desirable to split the leather along the medial back portion of the cover to provide flaps under which a back plate may be fastened for anchoring the leaf-holding mechanism thereto. This invention has for its object a new and improved apparatus for slitting the leather to receive the back plate and for scoring the same to provide a hinge joint. The apparatus is exceedingly simple and results in a great saving of time, labor and expensive machinery.

The invention comprises the novel apparatus hereinafter described and more particularly pointed out and defined in the appended claims.

In the accompanying drawings which illustrate a preferred form of apparatus and in which similar reference numerals refer to similar features in the different views:

Figure 1 is a top plan view of the apparatus involving this invention.

Figure 2 is a side elevational view of the apparatus.

Figure 3 is a sectional view taken upon the line III—III of Figure 1, looking in the direction of the arrows and showing the ram in elevation.

Figure 4 is an enlarged sectional view taken upon the line IV—IV of Figure 1 with parts omitted.

Figure 5 is an enlarged sectional view taken upon the line V—V of Figure 1, showing the platform elevated.

Figure 6 is an enlarged bottom plan view of the ram.

Figure 7 is an enlarged fragmentary sectional view of the ram taken upon the line VII—VII of Figure 6.

Figure 8 is an enlarged sectional view taken upon the line VIII—VIII of Figure 4.

Figures 9 and 10 are fragmentary elevational views of slitting members involving this invention.

According to this invention, a piece of leather or the like is supported and clamped in flatwise position, preferably by means of an upwardly yieldable support. Then beginning at one end of the sheet of leather, a vertical slit and adjacent horizontal slits are simultaneously formed lengthwise of the sheet to provide a pair of flaps underneath of which a metal plate may be fastened.

The illustrated apparatus consists of a longitudinally extending base member 1. A pair of filler blocks 2 (Figure 3) extend transversely of the base 1 adjacent the ends thereof to provide a space 3 therebetween for a purpose that will later appear. A ram guide member 5 is supported upon the filler blocks 2. This guide member consists of spaced side walls 6 which are provided with longitudinally extending guide grooves 7 (Figure 5) for receiving ribs 8 upon the sides of a reciprocable ram 9 which fits in the guideway formed by the spaced walls 6. The bottom of the ram guide is cut out in alignment with the space 3 between the filler blocks 2 as shown in Figure 3 and a yieldable bottom or support 10 is positioned in such cut out bottom and supported in alignment with the bottom by means of coil springs 11 positioned in sockets 12 in the base member 1. The yieldable support 10 forms the main support for the leather to be slit. This yielding support has bifurcated ends which receive the filler blocks 2. The forks 10^a extend beyond the open space 3 as shown in Figure 2 for a purpose that will later appear.

It will be noted that the springs 11 normally tend to force the support 10 upwardly and when it is desired to place a piece of leather upon the support 10, it is necessary to depress the same as shown in Figure 2. This supporting platform 10 is adapted to be automatically depressed during the reciprocating movement of the ram 9. To this end, a pair of pawls or dogs 13 are pivoted intermediate their ends to each side of the guide member 5 and each pair of dogs are pivotally connected in tandem by a rod 15. These dogs 13 are located over the forks 10^a of the supporting platform 10.

The aforementioned ram 9 carries a cross head 16 shown in Figures 1, 2, and 3 but omitted in Figure 4. A dog 17 is pivoted intermediate its ends to each end of the cross head 16 in the plane of the adjacent dog 13. The dogs 17 have lower hooked ends (Figure 2) adapted for engaging the forward dogs 13 and swinging the same for releasing the spring pressed platform 10 when the same is started forward on its working stroke whereby the platform 10 will be pressed upwardly by the springs 11 to bring the leather supported thereon in proper position for the slitting element later to be described. Upon the back stroke of the ram, the cam surfaces 17^b constituting the backs of the hook shaped portions of the dogs 17 will ride over the tops of the levers 13 which will have been moved to vertical position for lowering the work platform 10 as will later

appear so that the slit cover may be removed, and a piece of leather may be inserted.

It is desirable to slit the leather at a predetermined distance from one lateral edge. To accomplish this, a plurality of rods 18 extend from the far side of the movable platform 10. A cylindrical support 19 also extends from said platform in parallel relation with the rods 10. An angle bar 20 is slidably mounted upon the rods 18. The angle bar 20 has a bearing 21 slidably mounted upon the support 19 and provided with a set screw 22 for securing the same in any adjusted position. It will be understood that one lateral edge of the leather cover 23 is adapted 15 to contact the upstanding flange of the angle bar 20, as shown in Figure 5. Consequently, the sliding adjustments of the angle bar 20 will determine the distance of the slit portion from the lateral edges of the cover. If desirable, an auxiliary platform 10^b (Figure 5) upon the near side of the platform may be used to support the leather cover as it is being slit.

The bottom of the ram 9 carries slitting mechanism for making a vertical slit in the leather 25 and two adjacent horizontal slits to provide flaps. While this mechanism may assume various forms, the preferred form has been illustrated and will now be specifically described. Upon the front end of the ram 9, there is a block 23, upon which 30 a plate 24 is supported, that projects rearwardly of the block (Figure 4). The shank 25 of the slitting element 26 extends through this plate and is vertically adjustable with respect thereto by means of the nuts 27 and 28 which are threaded 35 upon said shank upon opposite sides of the plate 24. The shank 25 extends through an aperture in a bearing 29 in the ram 9.

The slitting element 26 which is secured upon the shank 25 consists of a forward point or apex 40 26^a and sloping sides 26^b shown more clearly in Figure 6. The slitting element may have a flat bottom as illustrated in Figures 7 and 10, or the bottom may be slightly concave as illustrated in connection with the slitting element 26^c shown in 45 Figure 9 wherein the bottom 26^d is shown concave. Likewise, the angularity of the portions of the slitting elements may be varied to produce a flat or tapering flap.

Adjacent the forward point of the slitting element, there is a shoe 30 having a V-shaped beveled notch 31 partly overlapped by the edges of the slitting element 26. The shoe 30 is attached to the yielding base 32 by means of a screw bolt 33 and slot 34 whereby the shoe may be longitudinally adjusted. The slit flaps pass between the shoe 30 and the slitting element and as it may be desired to vary the thickness of the flaps, the shoe is made longitudinally adjustable. The shoe also serves to smooth the leather in advance 55 of the slitting element and to guide the flaps upwardly and outwardly. It will be noted that the ram is reduced in thickness rearward of the slitting tool, so a sufficient space occurs between the bottom of the shoe against which the leather 60 is pressed and such reduced portion to allow the slit flaps to flex upwardly and outwardly. The slitting element is also adapted to be vertically adjusted with respect to the shoe to determine the depth of cut. The yielding base 32 is attached to the bottom of the ram by a pair of 65 screw bolts 35 and 36 for vertical movement toward and from the bottom of the ram. A spring confining chamber 37 surrounds the outer portion of the bolt 35 and a coil spring 38 in said 70 chamber bears against the shoe 30, whereby such

shoe becomes yieldably supported upon the ram.

Adjacent the rear end of the shoe 30, there is a second shoe 39 which is secured to the bottom of the ram and which is notched as indicated at 40 in Figure 6 to accommodate a rotary cutting element 41, which is designed to travel in advance of the slitting element 26 and make a vertical cut in the leather in alignment with the apex 26^a of the slitting element. This shoe 39 bridges the gap between the shoe 30 and the rotary slitting element 41. It will, of course, be understood that the rotary cutter 41 cuts only partially through the leather and substantially to the same depth as the slitting element. The ram 9 is provided with a pair of yielding tongues 42 with a space between said tongues to receive the rotary cutting element 41. Suitable recesses 43 are provided in the ram adjacent the outer sides of the tongues 42 for the reception of suitable scoring rolls 44 which, in the present instance, are illustrated as having V-shaped peripheries. These scoring rolls are designed to score the book covers to provide a more flexible hinge joint for the side portions thereof. The scoring rolls 44 and the rotary cutting element 41 are secured upon a shaft 45 journalled in the resilient tongues 42. One or more adjustable screws 46 (Figure 4) may extend through the ram 9 and engage the tongues 42 for adjusting the same to lower or raise the rotary cutting element 41 and scoring rolls 44 with respect to the bottom of the ram in order that the depth of cut may be varied.

The ram 9 is adapted to be reciprocated when in use. This may be manually done or may be performed by some suitable power means and for this purpose, a T-slot 47 (Figure 1) is provided in the outer end of the ram for receiving a pneumatically operated plunger 47^a. In order to limit the forward movement of the ram, a yoke 48 may be attached to the aforementioned block 23. This yoke is shown as having terminal depending arms 48^a which strike the lugs 13^a of the rear dogs 13 when the slitting element reaches the end of the leather cover for arresting further movement of the ram. The levers 13 will of course be inclined rearwardly and the lower portions will be extending forwardly when the leather platform is elevated. The lower portions of the rear levers 13 have laterally projecting lugs 13^a that lie in the path of the arms 48^a. When these arms 48^a strike the lugs 13^a, the levers 13 will swing to vertical position and lower the leather platform for removal of the leather and the insertion of a new piece.

In the position of parts as shown in Figure 2, the ram is in its starting position and the leather supporting platform 10 is in its lowered position so that a leather cover or the like may be inserted in the machine upon the platform 10. The ram 9 may then be advanced for tripping the dogs 13 and allowing the platform 10 to rise and bring the leather in the proper plane for the slitting element to cut in the edge thereof. As the ram is further advanced, the rotary cutter 41 will make a slight vertical cut in the leather in alignment with the apex of the slitting element and the scoring rolls will score the hinges. The slitting element will make horizontal slits extending from the vertical cuts to form suitable flaps which will flex upwardly over the sides of the slitting element as it advances. When the cover has been slit from end to end, the ram will be arrested as previously explained, and the platform 10 will be lowered by the righting of the

levers 13 by the arms 48^a. In returning, the pawls 17 will ride over the levers 13.

From the foregoing, it will be appreciated that a very simple apparatus has been invented for 5 making book covers, in which the flaps may be cut to any desired depths, and in which the covers may be scored at the same time that the slitting operation is performed, whereby a great deal of time and labor may be saved. Further, the 10 apparatus is very efficient in that very few, if any covers are spoiled or result in waste.

We are aware that many changes may be made and numerous details of construction may be varied through a wide range without departing 15 from the principles of this invention, and we, therefore, do not purpose limiting the patent granted hereon otherwise than is necessitated by the prior art.

We claim as our invention:

20 1. In a leather slitting machine, a supporting platform for maintaining the leather flatwise, a reciprocable member having a rotary cutter for making a vertical incision, slitting elements for making lateral incisions from said vertical incision, and scoring rolls for scoring the leather and means for guiding said member.

25 2. In a leather slitting machine, a member having a guideway with an open bottom, a platform yieldably supported below said member, a ram embodying cutting elements in said guideway, and means actuated by movement of said ram for depressing said platform.

30 3. In a leather slitting machine, a supporting platform, a member forming a guideway along one surface of said platform, and a reciprocable ram mounted in said guideway, leather cutting elements for making a vertical incision and adjacent lateral incisions carried by said ram and scoring rolls for forming hinge joints mounted 40 upon said ram.

35 4. In a leather slitting apparatus, a cutting element for making a vertical incision in the leather, slitting elements for making lateral incisions from said vertical incisions for forming flaps, scoring elements for forming hinge joints in the leather and means for simultaneously actuating 45 said elements.

50 5. In an apparatus for slitting flaps from leather, means forming a guideway, a reciprocating ram mounted in said guideway, a V-shaped cutting tool having a shank extending through said ram, a leather supporting platform beneath said ram, a yielding base attached to the bottom of the ram forward of said tool, a shoe attached 55 to said yielding base, and yielding means for urging said platform toward said shoe.

60 6. In an apparatus for slitting flaps from leather, means forming a guideway, a ram mounted in said guideway, a yielding base upon the bottom of said ram, a shoe having a V-shaped notch secured to said base, a V-shaped cutting tool mounted upon said ram, and cooperating with

said shoe, and a leather supporting platform beneath said ram.

7. In an apparatus for slitting flaps from leather, a leather supporting platform, means for guiding a ram for reciprocable movements above said platform, a rotary cutting element upon said ram, a V-shaped cutting tool upon said ram rearward of said cutting element, a shoe upon the bottom of the ram forward of said cutting tool and means for yieldingly urging said platform toward said shoe. 80

8. In an apparatus for slitting flaps from leather, a leather supporting platform, means forming a guideway above said platform, a reciprocable ram mounted in said guideway, a cutting element mounted upon said ram for making a vertical slit in said leather and a V-shaped tool mounted upon said ram rearwardly of said cutting element for cutting flaps in said leather from said vertical slit, said ram having provision 85 at its bottom to allow said cut flaps to flex upwardly and outwardly. 90

9. In a leather slitting apparatus, a leather supporting platform, a reciprocal member, a rotary cutting element mounted upon said member 100 for making a vertical incision in said leather and a slitting element upon said ram rearward of said rotary cutting element for making lateral incisions from said vertical incision for producing flaps, and means for guiding said member for 105 movement in a straight path, said member having provisions to allow said flaps to flex with respect to the plane of said leather. 100

10. In a leather slitting machine, means forming a guideway, a reciprocable ram mounted in 110 said guideway, slitting elements carried by said ram, a leather supporting platform beneath said ram, yielding means for normally urging said platform toward said ram, levers connected in tandem pivoted to said first mentioned means for engaging said platform, and means carried by said ram for actuating said levers. 115

11. In an apparatus for cutting flaps from leather, a pair of spaced walls having opposed grooves, a reciprocating member between said 120 walls having lateral extending guide parts located in said grooves, a leather cutting element upon said member, a flap slitting element behind and in spaced relation to said cutting element, and a leather supporting platform beneath said walls. 125

12. In an apparatus for cutting flaps from leather, a pair of spaced guide members, a ram having guide parts cooperating with said members for movement in a rectilinear path, a cutting tool on the bottom of the ram for making a vertical incision in the leather, a V-shaped cutting tool on said ram rearward of said first tool for severing flaps from the leather, and a leather supporting platform beneath said ram. 130
